Claims priority, application Australia May 14, 1958
21 Claims. (Cl. 317—99)

This invention relates to enclosures or cabinets for multi-wire electrical cable terminals and refers especially to such enclosures and cabinets which are designed to house and protect from accidental damage and atmospheric conditions the cross-connections between terminals of several multi-wire cables. Such enclosures or cabinets are hereinafter referred to as cross-connecting cabinets. The invention also includes an improved terminal unit for use in a cross-connecting cabinet and an improved arrangement for effecting the cross-connections.

Cross-connecting cabinets are commonly used in wire communication networks to provide easily accessible terminations for individual conductors of one or a number of cables at a common point. Cross-connections between the various conductors may be made and altered at this point, thus rendering the cable network adaptable for changing requirements of use, reducing the lengths of cable needed and facilitating maintenance and fault-tracing in the network. Cross-connecting cabinets normally enclose many pairs of individual communication circuit terminals, which are located in close proximity to each other. Accordingly the insulation resistance between the terminals of different circuits should be maintained at a high value in order to prevent cross-talk and short-circuits, caused by leakage between the various terminals, with the consequent degrading of the electrical characteristics of the whole network.

Presently used cross-connecting cabinets are generally either ventilated or hermetically sealed. Cabinets of the former type suffer from the disadvantages that the humidity of air inside the cabinet is the same as the humidity of the air outside the cabinet and that dust and other foreign matter may enter into the cabinet. If such ventilated cabinets are located out of doors, changing atmospheric conditions may cause considerable condensation of moisture inside the cabinet. Accumulation of moisture between the terminals of different circuits assists the formation of leakage paths therebetween and accordingly a reduced and often varying insulation resistance between the varying circuits results. Under extreme atmospheric conditions, and during floods, the electrical leakage may become so marked that the whole network becomes inoperable.

Presently used hermetically sealed cross-connecting cabinets usually employ an elastic compression seal located around a door or other opening through which access to the cabinet may be gained. These seals are rarely effective in use since the cabinets are generally of a light construction and thus the wall of the cabinet, or the door itself often tends to warp or buckle under the compressive force exerted by the seal. The seals may also fail to adhere to the cabinet after being in use for some time and tend to develop a permanent set thereby becoming ineffective. If the door or opening is located in a horizontal plane, then dirt, dust and other foreign matter may enter the cabinet and lodge between the sealing surfaces, thereby impairing the quality of the seal. Cross-connecting cabinets with leaking seals suffer from the same principal disadvantage of condensation as described above with reference to ventilated cabinets.

It is the principal object of the present invention to provide an improved cross-connecting cabinet of the her-

2

metically sealed type in which the above-mentioned disadvantages are overcome.

Another object of the invention is to provide a hermetically sealed cross-connecting cabinet in which the terminal units can be arranged compactly so as to reduce as far as possible the amount of enclosed air thereby minimizing the condensation of moisture within the cabinet.

10 A further object of the invention is to provide a hermetically sealed cross-connecting cabinet in which the seals are adapted to withstand vibrations and minor shocks, without impairing their efficiency.

15 Yet another object of the present invention is to provide a hermetically sealed cross-connecting cabinet which is adapted to accommodate a varying number of cables and in which the cross-connections between the terminals of the cables are effected in a systematic and easily traceable manner.

20 Further objects and aims of the present invention will become apparent from the ensuing description of a particular embodiment thereof.

According to the invention, a cross-connecting cabinet of the hermetically sealed type comprises a base portion having a cylindrical surface adapted to receive a rolling ring seal, a face containing circular apertures adapted to receive rolling ring seals whereby either terminal units and/or sealing plugs may be retained and hermetically sealed therein, a cover adapted to fit over the base portion, a rolling ring seal on the said cylindrical surface adapted to be rolled into a sealing position between the said surface and the cover by movement of the cover over the base portion in the axial direction of the said surface, means to locate, guide and move the cover over the base portion, and means to secure the cover in position on the base portion.

30 According to one aspect of the invention the said means comprise a flexibly supported hollow column on the cover and a spindle on the base portion adapted to fit within said hollow column. A further hollow outer column may be provided on the base portion to fit over the said hollow column.

35 According to a further aspect of the invention a terminal unit for use in the cabinet may comprise an elongated prismatic body member of dielectric material having a central longitudinal recess and one or more longitudinally disposed shoulders on each side of the groove, terminal tags located on these shoulders and a further series of tags which are staggered in relation to the terminal tags and are mounted adjacent the said central recess. The 40 terminal units are arranged to extend in directions parallel to the longitudinal dimension of the cabinet and are supported by a series of guard members hereinafter called jumper guards which are attached to the base portion and the hollow outer column. The connection between the 45 jumper guards and the terminal units are made through rings on the jumper guards, hereinafter called jumper rings, which are designed to fit within, and be secured to, the base or inner surface of the recess in the terminal unit. These jumper rings also serve to locate the cross- 50 connecting or jumpering wires within the recess of each terminal unit.

55 To facilitate the cross-connecting of corresponding terminals of adjacent terminal units, the terminals on each terminal unit are preferably arranged so as to provide an inner and an outer terminal. Corresponding inner terminals of adjacent terminal units may be directly connected by a removable conducting link, and similar connections may be made between corresponding outer terminals of adjacent terminal units. The arrangement of the terminals to provide an inner and an outer terminal is conveniently achieved by bringing out each pair of conductors to a pair of terminal tags and mounting the

tags on a stepped base, or alternatively by making the inner tags longer than the outer tags. For ease of manufacture, handling and sealing the body of the cabinet is preferably circular in horizontal cross-section.

Various other features and advantages of the invention will now be described with reference to the presently preferred embodiment of the invention which is illustrated in the accompanying drawings, in which:

FIGURE 1 is a side elevation of a cross-connecting cabinet in the closed position, the broken lines indicating the extent to which the cover may be raised while still engaged with the cabinet.

FIGURE 2 is an enlarged cross-sectional view of the cabinet shown in FIGURE 1, showing also the cross-section of a terminal unit and a sealing plug.

FIGURE 3 is a sectional view along the line 3—3 in FIGURE 2, and

FIGURE 4 is a sectional perspective view of two adjacent terminal units showing the method of direct cross-connection between corresponding tags thereon.

In this arrangement, the body of the cabinet is generally cylindrical in form and comprises three main parts—base 5, cover 6 and cap 7—which are cast from aluminum alloy, or other suitable material, and sand blasted on their external surfaces to give a uniform mat finish. The base portion 5 of the cabinet is in the form of a hollow cylinder having its upper end closed and its lower end provided with flanges 8, whereby the base can be secured to a foundation. The upper face of the base 5 is provided adjacent its periphery with several upwardly directed equally spaced circular apertures 9 which are adapted to receive and retain in position cable terminal units 10, or specially provided sealing plugs 11, which are used to close the apertures when there are fewer terminal units used than there are apertures. A hollow, vertically disposed column 12 is rigidly fixed to the centre of the base portion 5, and is provided internally with a co-axial spindle 13, which extends to at least the height of the hollow outer column 12, and has an externally screw-threaded shank portion 14 at its upper end. The spindle 13 is of such dimensions as to enable it to penetrate inside another hollow column, hereafter called the inner column 15, which is attached to the cover 6 of the cabinet and fits loosely over the said spindle 13. The loose sliding engagement between the inner column 15 and the spindle 13 helps to guide the cover 6 on to the base 5. Attached to the hollow outer column 12 and the base portion 5 there is a system of spaced vertical wires hereinafter referred to as jumper guards 16. These jumper guards 16 are removably attached to the base portion 5 of the cabinet and are adapted to support terminal units 10 in position by orientating them in a vertical plane and about a vertical axis. The jumper guards 16 also serve as a convenient place to which cable sheaths or screens can be connected for earthing purposes. Each of these jumper guards 16 has several horizontally disposed rings, hereinafter referred to as jumper rings 17, attached to it, which act as guides for cross-connecting jumpering wires as described hereinafter. The terminal units 10, and any sealing plugs 11 used when there are insufficient terminal units to fill all the apertures 9 in the base portion 5, are provided with rolling elastomeric ring seals 18, which provide an airtight joint between the base portion 5 of the cabinet and the terminal units 10 or sealing plugs 11.

The cover 6 of the cabinet is bell-shaped and provided internally with a hollow axial inner column 15, as referred to above, which is adapted to fit inside the hollow column provided on the base portion 12, and slide loosely over the spindle 13, as described above. This inner column 15 is flexibly retained in the top portion of the cover 6 of the cabinet by a part-spherical metal ball seating 19 or similar means, which allow the cover 6 to remain self-aligning relatively to the sealing ring 20 on the base portion 5 of the cabinet.

The cover 6 is adapted to fit over the terminal units 10 and engage with the base portion 5 of the cabinet, thus completely enclosing the terminal units 10. The upper end of the cover 6 is provided externally with a captive nut 21, which is provided with a flange 22, which underlies an annular shoulder 23 on a member 24, which is rigidly mounted on the upper end of the cover 6. The captive nut 21 is arranged to threadably engage the shank portion 14 of the spindle 13, and is provided with a compressible ring seal 25 of resilient material, or alternatively, a rolling elastomeric ring may be used to effect the sealing between the spindle 13 and the cover 6. The compressible ring seal 25 is designed to minimise relative motion between it and the metal surfaces 15 confining it, when the ring seal 25 is compressed, as this could damage it especially after repeated closing and opening of the cover 6. This seal 25 is adapted, on tightening of the nut 21, to completely seal the portion of the cover 6 through which the spindle 13 projects.

20 The internal diameter of the ring seal 25 is greater (when the seal is not under compression) than the external diameter of the shank portion 14 of the spindle to enable the latter to move freely through the ring seal when the cover is being raised and lowered. By such a screwing action the cover 6 is forced downwardly over the outer surfaces 26 of the base portion 5, where it is arranged to engage with a rolling neoprene ring seal 20, which provides an airtight joint between the cover 6 and the base portion 5 of the cabinet.

30 The cover is provided with a cap 7 which is adapted to threadably engage the externally projecting shank portion 14 of the spindle 13. The cap 7 is fitted with a tumbler lock 27, enabling the cabinet to be made secure after the cap 7 has been screwed down. Removal of the cap gives access to the captive nut 21 on the top of the cover. By unscrewing the nut the flange 22 on the same raises the cover off the base, after relaxing the ring sealing member 25 surrounding the shank portion 14 of the spindle. When the cover is raised in this way, the rolling ring seal 20 between the cover and the base is rolled to a loose or non-active position in the groove 28 and the nut 21 is then further unscrewed until it disengages from the shank 14 of the spindle, whereupon the cover can be raised to a position where the enclosed terminal units 10 are fully accessible. The cover is held in this raised position by a spring-controlled latch 29, which is attached to the hollow base column 12 and is adapted to coact with an annular abutment 40 secured to the inner column 15 when the cover is raised, thus permitting working access to the terminal units and the jumpering connections without the complete removal of the cover.

35 The cable terminal units 10 are formed from epoxy or other suitable casting resin with a horizontal cross-section, generally in the form of a truncated sector of a circle. The outer surface of each unit is formed in a stepped configuration and the central portion of the said surface is recessed to provide accommodation for jumpering wires as referred to hereinafter. The steps 30, 31 on each side of, and the said recess 32 in, the unit are so disposed as to provide a radially symmetrical horizontal section. The terminal unit, when placed in position vertically in an aperture in the base portion of the cabinet, is secured in its vertical position by means of jumper rings 17 which are themselves attached to a jumper guard 16. The terminal tags 33 of the terminal unit are disposed in straight lines, one line on each step of the terminal unit. Thus, on each terminal there are, on each side of the recess 32, separate lines of inner and outer tags, the inner tags 34 being disposed adjacent the recess and projecting radially outwards beyond the outer tags 35 which are located on the steps remote from the recess. A multi-wire cable 36 enters a terminal unit through a cylindrical base portion 37 from below, and the individual conductors, which may be either dry paper or plastic insulated, are then connected to the corresponding terminal tags on the terminal unit, these connections being

embedded within the epoxy resin which forms the body of the terminal unit. The moulded body of the terminal unit also provides an airtight seal for the cable, which is essential if the cable is gas-filled. The epoxy resin used has a high order of volume and surface resistivity, and thus provides for good insulation between the tags.

Where the cable is provided with a metal sheath or screen, provision is made to earth this sheath or screen by attaching it to metal inserts in the terminal units, which inserts are connected through the jumper guards 10 16 to the metal body of the cabinet.

The stepped form of the terminal unit permits the use of direct connections between corresponding tags on adjacent terminal units by means of solid connecting links 38, thus greatly simplifying the cross-connecting circuitry. Each terminal unit is further provided with two vertical rows of tags of insulating material, referred to as fanning strips 39. These rows or fanning strips are disposed on either side of the central recess in the terminal unit, and the fanning tags are staggered, in a vertical direction, in relation to the terminal tags, so that the cross-connecting or jumpering wires can be supported by these fanning tags without coming into contact with nearby terminal tags. The central recess in each terminal unit is adapted to receive these jumpering wires and lead them either upwardly or downwardly, either to other terminal tags on the same terminal unit, or to terminal tags on another terminal unit within the cabinet. This recess 32 in each terminal unit, is also slotted horizontally to receive the jumper rings 17 attached to the jumper guard 16, which rings further serve to confine the jumpering wires within the central recess 32. The stepped formation of the portion of the terminal unit body on which the adjacent rows of terminal tags are mounted also has the beneficial effect of greatly increasing the surface leakage path between these rows of tags.

According to an alternative embodiment of the invention the base portion may be formed as a conduit enclosing the lead-in cables and embedded directly in concrete or any other suitable foundation.

In a modified form of the invention, the fanning tags, jumper rings and jumper guard may be made integrally as one unit. This integral unit comprises a channel-shaped metal member, extending the length of the terminal unit and adapted to be inserted in, and attached to the bottom of, the central recess of said terminal unit, and a jumper guard which is integrally attached to the said channel member by several semi-circular brackets. The walls of the channel section extend outwards beyond the body of the terminal unit for a distance approximately equal to the depth of the central recess in the body of the terminal unit. The portions of the walls of the channel member extending outwards beyond the body of the terminal unit are symmetrically slotted along their whole length to provide a series of spaced outwardly directed fingers, which are used to fan out the jumpering wires of the terminal unit. The jumper guard is preferably attached to the channel member through several semi-circular brackets which are welded to corresponding fingers, referred to above. A fanning tag and jumper guard assembly of the type described above stiffens considerably the terminal unit and simplifies the manufacture thereof, and this is especially advantageous as the epoxy casting resin used takes about three days to harden completely after moulding, and in that time could easily bend, twist or warp if not stiffened. Further, the metal fanning tag and jumper guard assembly provides a convenient earthing point for the sheath of the cable, and also serves to protect the terminal unit during handling and transport prior to insertion in a cross-connecting cabinet.

Miniatuerised square section tinned steel terminal tags have been adopted to enable a tool, which requires a tag of this form, to be used for connecting the jumpering wires to the tags by a solderless wrapping technique. Conventional soldering methods can also be used on these tags.

The cross-connection between corresponding tags on

adjacent terminal units can be effected by means of channel-shaped jumper links, which are placed in position over the corresponding terminal tags and soldered to them. Tags which bear important circuits, such as burglar or fire alarms, are normally covered by a piece of insulating tubing in order to prevent these circuits from being accidentally short-circuited or earthed during maintenance operations on the cabinet.

The cross-connecting cabinet as described above is eminently suitable for the housing of cross-connections of communication cables. It is easily accessible, sufficiently strong to resist accidental damage from vibrations and shock, and withstand submerging in water, i.e. it is flood-proof. The sealing arrangements ensure that changing atmospheric conditions do not affect the terminal connections in any way. The seals are easily accessible and easy to maintain in a good condition. It is important to achieve complete hermetic sealing of the terminal units, because the condensation of moisture from the air on to the surfaces of the units could provide a short-circuit path between the tags. The stepped terminal unit construction and the use of epoxy casting resin greatly improves the insulation resistance between adjacent rows of tags, as well as rendering possible the simple direct connection between corresponding tags in adjacent units described herein. The jumpering wires are disposed in the unit recesses, and this renders subsequent maintenance and inspection work much easier than in presently used cross-connection systems, as well as protecting the jumpering wires from accidental damage during such work. The cross-connecting cabinet as described herein has also a great degree of flexibility, as the number of circuit terminals to be enclosed can be varied widely by using the required number of terminal units only, and inserting sealing plugs in the unoccupied apertures in the base portion of the cabinet.

What I claim is:

1. A cross-connecting cabinet of the hermetically sealed type comprising a base portion having a cylindrical surface adapted to receive a rolling ring seal, a face containing circular apertures adapted to receive rolling ring seals whereby terminal units and sealing plugs may be selectively retained and hermetically sealed therein, a cover adapted to fit over the base portion, a rolling ring seal on the said cylindrical surface adapted to be rolled into a sealing position between the said surface and the cover by movement of the cover over the base portion in the axial direction of the said surface, means to locate, guide and move the cover over the base portion, and means to secure the cover in position on the base portion.
2. A cross-connecting cabinet as claimed in claim 1, in which the first said means comprise a longitudinally extending hollow column attached centrally to the inside of the cover and a centrally located upwardly directed spindle adapted to fit within said hollow column with slight clearance.
3. A cross-connecting cabinet as claimed in claim 2, in which the hollow column is attached to the cover in a part-spherical ball seating, which allows the hollow column to pivot at its point of attachment to the cover.
4. A cross-connecting cabinet as claimed in claim 2, in which the spindle extends through the cover when the cover is in the closed position and forms an externally screw-threaded shank portion.
5. A cross-connecting cabinet as claimed in claim 4, in which the cover includes an internally screw-threaded portion, which is adapted to engage the shank portion of the spindle.
6. A cross-connecting cabinet as claimed in claim 5, in which the said internally screw-threaded portion comprises a nut which is free to rotate about a fixed axis but is held translationally captive relative to the cover.
7. A cross-connecting cabinet as claimed in claim 2, in which the cover includes a protected compression seal, adapted to seal the cover against the spindle when the cover is in the closed position.

8. A cross-connecting cabinet as claimed in claim 1, in which the cylindrical surface of the base portion is provided with a groove into which the rolling ring seal is displaced when the cover of the cabinet is raised and from which the rolling ring seal is displaced when the cover is lowered.

9. A cross-connecting cabinet as claimed in claim 2, in which the first said means also includes a hollow outer column, which is concentric with the spindle and is adapted to receive the said hollow column on the cover with a slight clearance.

10. A cross-connecting cabinet as claimed in claim 9, comprising a spring-controlled latch which is adapted to support the cover in the raised position and which is attached to the hollow outer column.

11. A cross-connecting cabinet as claimed in claim 9 comprising a system of longitudinally extending jumper guards attached to the hollow outer column and the base portion of the cabinet.

12. A cross-connecting cabinet as claimed in claim 11, comprising horizontally disposed jumper rings and terminal units connected to the jumper guards by means of said horizontally disposed jumper rings.

13. A cross-connecting cabinet as claimed in claim 12, in which the terminal units each comprise a longitudinal prismatic body portion of dielectric material, having two or more longitudinally extending rows of terminal tags.

14. A cross-connecting cabinet as claimed in claim 13, in which the dielectric body portion of a terminal unit is provided with a central, longitudinal recess, to a surface to which said jumper rings are connected.

15. A cross-connecting cabinet as claimed in claim 14, comprising at least one row of terminal tags arranged on each side of the central recess.

16. A cross-connecting cabinet as claimed in claim 15, comprising a plurality of rows and longitudinally extending steps formed in the dielectric body portion.

17. A cross-connecting cabinet as claimed in claim 16, in which the arrangement of terminal tags on a terminal unit, and the arrangement of terminal units in the base portion of the cabinet, are such that corresponding tags of adjacent terminal units may be connected by direct rigid, conducting links.

18. A cross-connecting cabinet as claimed in claim 17, in which the terminal units include, on each side of the central recess, a row of fanning tags.

19. A cross-connecting cabinet as claimed in claim 18, in which the fanning tags are staggered, in the longitudinal direction of the terminal unit, in relation to the terminal tags.

20. A cross-connecting cabinet as claimed in claim 19, in which the fanning tags, jumper rings and jumper guard are formed integrally as one unit, which is attached to a surface of the central recess in a terminal unit.

21. A cross-connecting cabinet as claimed in claim 6, comprising a lock and in which the means to secure the cover in position on the base portion comprises a cap which is adapted to be screwed on to the shank portion of the spindle and retained in a tightened position thereon by means of said lock.
